US0D1026369S

(12) **United States Design Patent** (10) Patent No.: **US D1,026,369 S**
(45) Date of Patent: ** May 7, 2024

(54) **DUST BOX ASSEMBLY**

(71) Applicant: **Falun Zhu**, Guangzhou (CN)

(72) Inventor: **Falun Zhu**, Guangzhou (CN)

(**) Term: **15 Years**

(21) Appl. No.: **29/914,938**

(22) Filed: **Oct. 24, 2023**

(51) LOC (14) Cl. **15-05**

(52) U.S. Cl.

USPC **D32/31**

(58) **Field of Classification Search**

USPC D7/550.1, 553.1, 553.2, 554.3; D15/147; D32/3, 25, 30, 31, 39

(57) **CLAIM**

The ornamental design for a dust box assembly, as shown and described.

DESCRIPTION

FIG. 1 is a front, left and bottom perspective view of a dust box assembly, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the dust box assembly that form no part of the claimed design.

1 Claim, 7 Drawing Sheets
